SWITCH FOR FLOOR LAMPS

Joseph M. Puffer, Melrose, Mass.

Application August 12, 1947, Serial No. 768,177

2 Claims. (Cl. 200—52)

1

This invention relates to improvements in switches for floor lamps and particularly floor lamps having combinations of bulbs which can be connected in various ways to give different degrees of illumination. A typical floor lamp may have a two-filament bulb and, in addition, three ordinary bulbs on a separate circuit.

Switches are customarily provided to permit the operator to turn on either or both filaments of the large lamp bulb, and to turn on one, two or three small lamp bulbs; however, the control switches are often somewhat inconveniently located and difficult to find in darkness or semi-darkness.

It is an object of the present invention to provide switches for lamps of this general description, the switches being conveniently located and easy to find and operate by the sense of touch.

It is a further object of the invention to provide improved switch structure enabling the operator to connect or disconnect the lamps in various combinations at will without the necessity of going through a cycle of combinations, as is customary with most lamps of this type.

For a more complete understanding of the invention, reference can be made to the following description thereof and to the drawing, of which

Figure 1 is a sectional view of a switch structure embodying the invention;

Figure 2 is a section on line 2—2 of Figure 1;

Figure 3 is a section on line 3—3 of Figure 1;

Figure 4 is an elevation of one of the members shown in Figure 1; and

Figure 5 is a plan view of the same.

Figure 1 illustrates a portion of the column of a floor lamp which is supported by the customary base (not shown) and, in turn, supports any desired combination of bulbs, sockets, reflectors, shades, etc., which are characteristic of floor lamps. At the center of the column is a stem 10 which may conveniently be an iron pipe. This is the member which provides mechanical strength for supporting the upper works of the lamp. This member can be utilized to serve as an electric current conductor, or, if preferred, a wire may be extended therethrough instead; as shown in Figure 1 it is supposed to be employed as a conductor.

Secured to an intermediate portion of the stem 10 at a convenient level are two collars 12 and 14 of insulating material, one of these collars being illustrated in Figures 4 and 5, the other collar being similar in structure. Each collar consists of a disk 16 having a central aperture

18 through which the stem 10 extends. A bracket 20 extends from the rim of the disk 16 in a direction parallel to the axis of the disk. On the bracket 20 are mounted two resilient switch elements 22 and 24, these elements being preferably strips of spring brass bent to desired shape.

The collars 12 and 14 are fixed to the stem 10 by any suitable means such as set screws 26. Between the collars 12 and 14, and supported thereby, is a metal cylinder 28 which is connected by the wire 30 to one pole of the house electrical circuit, the stem 10 being connected to the other pole. The cylinder 28 serves as a switch element or distributor to connect the wire 30 selectively with either or both of the switch elements 22 and 24. In like manner, the lower collar 14 supports a pair of switch elements 32 and 34. The switch elements 22, 24, 32 and 34 tend to press against the charged distributor 28 and are connected respectively through the various lead wires 36, 38, 40 and 42 to the several lamps supported by the column. The wires 40 and 42 pass through suitable apertures 44 in the collars 12 and 14.

In order to disconnect the switch elements from the distributor 28, I provide two sleeves 50 and 52 which fit loosely on and are rotatable about the upper and lower portions respectively 30 of the distributor 28. These sleeves are provided with disks or flanges 54 and 56, respectively, having cylindrical rims 57 and 58 which can be conveniently grasped to rotate the sleeves.

The upper sleeve 50 is peripherally grooved as 35 at 60 and 62, the spring conductors 22 and 24 riding in these respective grooves. As shown in Figure 2, the groove 60 is provided with a number of shallow recesses 66 and two apertures 68 and 70, the apertures being of sufficient size 40 to permit the element 22 to come in contact with the distributor 28 when one of these apertures registers with the switch element. In like manner, the lower groove 62, as shown in Figure 3, is provided with a series of recesses 72 and two apertures 74 and 76, through which the switch elements 24 can press against the distributor 28.

When the sleeve 50 is in the angular position shown in Figures 2 and 3, the element 22 is in contact with the distributor 28 but the element 50 24 is held out of contact therewith. Thus, the wire 36 is in a completed circuit through the lamp or lamp filament to which it is connected, whereas, the wire 38 is disconnected from the distributor 28 and, consequently, is in an open circuit. If the sleeve 50 is rotated so that the

apertures 70 and 74 register with the elements 22 and 24, then both wires 36 and 38 are in closed circuits. It is also evident that when the aperture 76 registers with the element 24 so as to put the wire 38 in a closed circuit, then the element 22 will be in one of the shallow recesses 66 and consequently out of contact with the distributor 28.

The lower sleeve 52 is provided with grooves, recesses and apertures similar to those of the sleeve 50 so that the conductors 32 and 34 can be connected singly or together in closed circuits through the respective lamps or filaments to which they are connected.

The column also includes a protective and ornamental sheath which is horizontally split so that it has an upper portion 80 which extends down from the lamp brackets to the flange 54, and a lower portion 82 which extends from the flange 56 down to the base of the column. The flanges 54 and 56 project outward through the split and the diameter of the rims 57 and 58 are preferably of greater diameter than that of the sheath. Hence, when the lamp is groped for in darkness and the column is found, the hand of the operator slides along the column until the rims 57 and 58 are felt. The rims are then easily rotated to turn on any desired combination of the bulbs in the lamp.

I claim:

1. In a floor lamp column, a central rigid stem, a metal cylinder surrounding an intermediate portion of said stem and electrically insulated therefrom, a plurality of resilient switch ele-

ments, means supporting said elements in position to contact said cylinder, a sleeve of insulating material on said cylinder between the cylinder and said switch elements, said sleeve having apertures therethrough to permit contact between the cylinders and the elements registering with said apertures, and a flange on said sleeve to facilitate rotation thereof.

2. In a floor lamp column, a central rigid stem, two spaced collars of insulating material secured to an intermediate portion of said stem, a metal cylinder supported between said collars around and spaced from said stem, a resilient switch element carried by one of said collars and arranged to press against said cylinder, a sleeve of insulating material loosely fitted on said cylinder and interposed between the cylinder and said switch element, said sleeve having an aperture therethrough to permit the element to touch the cylinder when the aperture registers with the element, and a flange on said sleeve having a rim manually engageable to rotate the sleeve so as to move said aperture into and out of registry with said switch element.
